NURSING BOTTLE

Ernest N. Perry, Lowell, Mass.

Application April 21, 1936, Serial No. 75,587

3 Claims. (Cl. 215—11)

This invention appertains to new and useful improvements in nursing bottles and more particularly to a novel nipple holding construction.

The principal object of the present invention is to provide a nipple holder for nursing bottles wherein means is provided permitting air to enter the nursing bottle as milk is drawn out by the infant.

Another important object of the invention is to provide means for nursing bottles which will prevent the occurrence of vacuum in the bottle which is a frequent cause of colic in children.

These and various other important objects and advantages of the invention will become apparent to the reader of the following specification.

In the drawings:

Figure 1 represents a side elevational view.

Figure 2 is a vertical sectional view.

Figure 3 is a horizontal section on line 3—3 of Figure 1.

Figure 4 is a bottom plan view of the stopper.

Figure 5 is a side elevational view of the stopper and nipple holder.

Figure 6 is a fragmentary vertical sectional view through the breathers and supporting stem.

Figure 7 is a fragmentary enlarged sectional view of one of the valves.

Referring to the drawings wherein like numerals designate like parts, it can be seen that numeral 5 represents the nursing bottle having the neck portion 6. Numeral 7 represents the cork stopper which has a metallic tube 8 extending therethrough and a substantial distance above the same to project into the shank 9 of the nipple holder 10 over which the nipple 11 is stretched as shown in Figure 2. Circumscribing the tube 8 and interposed between the holder 9 and the stopper 7 is the ring 12 above which spring arms 13 depend to engage over the bead 14 on the neck 6 of the bottle.

Extending through the side of the cork 7 and the tube 8 is the laterally bent upper end of the stem 15 which engages into the manifold 16 at its lower end. From this manifold extends laterally the resilient tubular members 17 which are se-

cured to the manifold 16 by tie members 18. Spreaders 19 fill the outer ends of these tubular members 17 which can be referred to as breathers.

It can now be seen, that as the infant sucks on the nipple 11 and some of the fluid is displaced from the bottle 5, air will enter the stem 15 and will be expelled through the tubular members 17 into the bottle. Thus no vacuum can occur in the bottle.

While the foregoing specification sets forth the invention in specific terms, it is to be understood that numerous changes in the shape, size and materials may be resorted to without departing from the spirit and scope of the invention as claimed hereinafter.

Having described the invention what is claimed as new is:

1. In a nursing bottle, a container, a stopper for the container, an elongated tubular stem extending in the bottle and opening through one side of the stopper beyond the container, a manifold at the inner end of the stem and air outlets in the manifold, and spring retaining members on the stopper for engaging the adjacent portion of the container for preventing displacement of the stopper from the container.

2. In a nursing bottle, a container, a stopper for the container, an elongated tubular stem extending in the bottle and opening through one side of the stopper beyond the container, a manifold at the inner end of the stem and air outlets in the manifold, and valvular means for the said air outlets, said outlets being in the form of elongated resilient tubular members provided with means for stretching the outer ends thereof.

3. In a nursing bottle, a container, a stopper for the container, an elongated tubular stem extending into the bottle and opening through one end of the stopper, beyond the container, the inner end of the tube being provided with a T-fitting and a flexible tube extending from the lateral portions of the T-fitting, said flexible tube being provided with spreaders in the open outer end portions thereof.
